UNITED STATES PATENT OFFICE.

DOMENIC M. CAMPANA, OF CHICAGO, ILLINOIS.

LINING GAUGE.

Application filed February 20, 1922. Serial No. 537,792.

To all whom it may concern:

Be it known that I, DOMENIC M. CAMPANA, a citizen of the United States, residing at Chicago, in the county of Cook and State of Illinois, have invented certain new and useful Improvements in Lining Gauges, of which the following is a specification.

This invention relates to a marker gauge or guide for use in connection with china and glass decoration and for other purposes of a similar nature.

The invention has for its object the provision of a gauge which shall be of improved construction, simple and economical to manufacture, and which shall be accurate and convenient in use.

The invention is exemplified in the combination and arrangement of parts shown in the accompanying drawing and described in the following specification and it is more particularly pointed out in the appended claims.

In the drawing,

Fig. 1 is a plan view, showing one embodiment of the invention as it is used for lining chinaware.

Fig. 2 is a perspective view of the device shown in Fig. 1.

Fig. 3 is a view similar to Fig. 1, showing a slightly modified construction.

In china and glass decoration the designs used frequently include lines or bands parallel with the periphery of a decorated article. The ordinary compass is impractical for use in drawing lines of this kind for the reason that it is difficult to locate the center of the article and it is practically impossible to retain a compass leg on a central point even if the point could be conveniently located. Applicant's invention contemplates guiding the marker from the periphery of the article rather than from the center, thus insuring the proper location of the decoration with respect to the periphery, to which the eye naturally relates the decoration rather than to the center.

In the form of the invention shown in Figs. 1 and 2, a piece of sheet metal is stamped or otherwise formed to provide spaced bars 10, connected at one end by a yoke 11 and having a cross-bar 12 adjustably mounted to slide along the bars 10. The bar 12 is bent backwardly about one of the members 10 to provide a contact piece 13 engaging the under side of the members 10. A set-screw 14 is threaded into the bar 12 to

engage the upper face of the bar 10 to retain the cross-bar in its adjusted position. It will be apparent that pressure of the screw 14 upon the bar 10 will spring the cross-bar upwardly so as to resiliently press the end of the screw against the bar 10. The ends of the bars 10 are bent to form hooks 15, which engage the periphery 16 of the article to be decorated, as shown in Fig. 1. A pencil or other suitable marker is placed at the juncture 17 of the bars 10 and 12, and by a tangential movement of the pencil the gauge is carried about the periphery of the article, forming a line shown at 18 in Fig. 1. The cross-bar 12 is adjusted along the bars 10 to give any spacing and any number of lines desired. The contact of the hooks 15 at spaced points on the periphery 16 insures accurate positioning of the marker at all points about the periphery of the article. In lining the outside of glass tumblers or similar devices, the hooks 15 rest upon the rim of the tumbler with the gauge hanging down on the outside. 80

Where lines or bands are to be placed relatively near the center of a plate or other disk-shaped object, the tangential pressure of the pencil might tend to throw the inner end of the gauge forwardly, creating an irregular movement of the marker. To overcome this difficulty a central disk 19 may be provided, to which the inner end of the gauge is pivoted at 20. A comparatively heavy soft metal such as lead may be used to advantage for this disk. This will prevent the inner end of the gauge from moving so as to bring either of the hooks 15 out of contact with the periphery of the plate and yet will permit slight movement of the pivot point 20 as the gauge is rotated if the pivot is not exactly centered on the plate. 95

In order to adjust the length of the arms 10 of the gauge to different sized articles, the arms may be made of relatively thin, easily bent material so that when the disk 19 is placed upon the center of the article to be decorated the ends of the arms 10 may be bent over the periphery of the plate to form the hooks 15. This will properly adjust the length of the arms for a set of plates of a given diameter, and when it is desired to use the device upon articles of a different diameter the ends may be bent in a different place to correspond to the different sized device. 105

It will be apparent that the process em-

ployed in this invention of guiding the marker from the periphery rather than the center of the article is more convenient than guiding from the center and has the advantage of always locating the decoration in proper relation to the periphery of the article, which is the part of the object with relation to which the position of the decoration is judged by the eye of the observer.

10 I claim:

1. A lining device comprising a pair of spaced bars having abutment members thereon for engaging the edge of an object to receive a line, the space between said bars being open and unobstructed adjacent said abutment members, and means adjustable along said bars for positioning a marker at various distances from the edge engaged by said abutment.

20 2. A lining device comprising a pair of sheet metal strips connected together at one end and having hooks formed on the opposite end thereof, the hooked ends of said bars being unconnected to provide an open space therebetween, and means adjustable along said strips for positioning a marker at various distances from said hooks.

30 3. A lining device comprising a pair of bars having hooks formed on adjacent ends thereof and having an unobstructed open space between said ends, a yoke connecting the opposite ends of said bars, and a cross-bar adjustably mounted between said yoke and hooks for positioning a marker at various distances from said hooks.

40 4. A lining device comprising sheet metal strips extending parallel with one another, a yoke connecting adjacent ends of said strips to retain said strips in spaced position, hooks formed on the opposite ends of said strips for engaging the edge of an object to be lined, a bar bent about the outer edge of one of said strips to form arms engaging opposite sides of said strip and extending 45 into position to engage opposite sides of the cooperating strip, and a set-screw threaded into one of the arms of said bar and engaging the strip opposite that about which said bar is bent to retain said bar in various positions of adjustment along said strips.

50 5. Means for forming lines on an object having a curved edge, comprising contact members for engaging said edge at two spaced points thereon while leaving the portion of said edge between said points free, a marker guide connected with said contact members, and means at the side of said edge adjacent said marker guide for holding said contact members in spaced relation with one another, said members being unconnected at the opposite side of said edge.

60 6. Means for lining circular objects, comprising a gauge for a marker having contact members for engaging the circular edge of said object to guide said marker in a line

parallel with said edge, said contact members being connected to one another at one side only of a straight line joining their points of contact, and a marker guide positioned on said side of said line.

70

7. Means for lining a circular object, comprising a gauge having two spaced contact members for engaging the curved edge of said object, an abutment member for a marker for holding said marker a fixed 75 distance from said edge during a lining operation and means positioned at the same side of said edge as said abutment member for holding said contact members in spaced relation with one another, the space between 80 said contact members at the opposite side of said edge being entirely open.

8. Means for lining circular objects, comprising a pair of elongated spaced members having abutments thereon for engaging the 85 edge of said object, and means adjustable along said members for retaining a marker at various distances from the edge engaged by said abutment members, the space between 90 said abutment members at said edge being open to accommodate the curvature of said edge.

9. A liner for an object having a curved edge comprising a pair of elongated members, means for holding said members in 95 spaced relation to one another, a contact member on each of said spaced members for engaging the curved edge of said object, and means adjustable along said members for retaining a marker in definite relation to the 100 curved edge of said object the space between said contact members being open to accommodate the curved portion of said edge.

10. A lining device comprising an elongated member having spaced contact members at one end thereof, and means for retaining the opposite end in approximately 105 fixed position while permitting said elongated members to be guided by said spaced contact members.

110

11. A lining device comprising an elongated member having a pair of spaced contact members for engaging a curved edge of an object to be lined, a pivotal support for the opposite end of said elongated member, and means intermediate said ends for guiding a marker.

115

12. A lining device comprising an elongated member having a pair of spaced contact members for engaging a curved edge 120 of an object to be lined, a pivotal support for the opposite end of said elongated member, and means intermediate said ends for guiding a marker, said pivotal support being movable to permit said elongated member to be guided by engagement of said spaced contact members with the curved edge of said object.

125

13. A lining device comprising an elongated member having a pair of spaced abut-

130

ment members thereon for engaging the curved edge of an object to be lined, a pivotal support for the opposite end of said elongated member comprising a relatively heavy weight to which said end is pivoted, and a marker guide adjustable along said member intermediate said ends.

14. A lining device comprising a pair of spaced elongated strips, means for retaining said strips in parallel relation with one

another, a pivotal support for one end of said strips, and a marker guide adjustable along said strips, the ends of said strips opposite said pivotal support being bent to form contact members for engaging an edge of an object to be lined.

In testimony whereof I have signed my name to this specification on this 17th day of February, A. D. 1922.

DOMENIC M. CAMPANA.
